UNITED STATES PATENT OFFICE

JOHN FRANCIS HARVEY TEMPLER, OF EALING, LONDON, ENGLAND

TRAWLING GEAR

Application filed November 5, 1928, Serial No. 317,374, and in Great Britain November 9, 1927.

The invention relates to trawling gear and especially to trawl boards, in some cases known as otter boards, for keeping open the mouths of fishing nets.

In certain forms of such boards, the towing warp is attached to the board at some little distance from the leading edge, thereby providing as it were a re-entrant angle and increasing the liability of the gear to foul submarine cables or other obstructions. Considerable expense is in this way incurred due to loss of or damage to nets, loss of time and so forth.

A main object of the present invention is to provide a form of board in which such a tendency to foul cables or other obstructions is reduced or eliminated.

With such an object, the present invention consists in a trawl board having the characteristics hereinafter described and particularly pointed out in the claims.

Referring to the accompanying drawings, which are of a diagrammatic nature and illustrate only certain forms of the invention by way of example:—

Figure 1 shows a diagram of a developed board in which the two operative areas are in one plane,

Figure 2 being a view to indicate the actual angle between the two parts of the board, while

Figure 3 shows a similar view of a modification in which the two parts of the board are merged into one another by a curve;

Figure 4 shows a plan view of such a board in about the position it assumes in use,

Figure 5 being a side view of the board as seen in the direction of the arrow, α , in Figure 4, and

Figure 6 a front view of the board as seen in the direction of the arrow, y , of Figure 4; while finally

Figure 7 shows a plan view of an alternative arrangement in which the board is towed by means of a streamer.

In carrying the invention into effect according to one form, see Figure 1, the developed and idealized board has the geometrical form of a rectilinear plane triangle, ABC, the towing warp or the like being secured

at the angle, B, either directly or by way of the usual bridle. To obtain the actual form of the board, a perpendicular, AD, is drawn from the angle, A, to the opposite side, BC, and the rear part, ACD, of the board is then bent about the line, AD, through an angle of about 45° as indicated in Figure 2.

Good results are secured in practice if the leading part of the board corresponding to the triangle, ABD, is double the area of the upturned portion, ADC, or in other words if BD is twice DC.

Structurally, the body of an otter board according to the present invention may be built up of wooden planks secured transversely to longitudinal steel formers, such formers serving to take the wear if the board is towed over the sea-bottom, but any other suitable construction may be used. In addition, stiffeners may be provided if desired and in particular one or more such stiffeners may connect the upturned front and rear parts of the board, so as to assist it to resist deforming forces.

A two-plane board in accordance with the present invention, towed through the water from its leading point will exercise, or may be ballasted or equivalently formed to exercise, a lifting (or diving) force in addition to a spreading force, by virtue of the hydrodynamic forces acting on it.

Such boards, right-handed on the one side of the net and left-handed on the other, may be secured to the towing tackle in different ways.

For example, referring to Figures 4, 5 and 6, both the towing warp, α , and the net rope, b , may be attached at the angle, B, of the board at a considerable distance in advance of the net, the direction of advance being shown by the arrowed chain line, AE. Under proper conditions for lift, the board will assume such a position that the points, B and C, are about level while the point, A, is at the lower level, a lifting and a spreading force being thus obtained.

If, however, by ballasting or inclining locally the forward or rearward edges of the planes, the point, A, rises to or above the level of D, the board will then exercise a div-

ing force in addition to the spreading force, thus providing a method of working sometimes useful in fishing "between depths."

Or again, (see Figure 7), the angle, B, of the board may be attached by a streamer, c, of any convenient length to a point in the towing warp, or alternatively, to the point where the towing warp is attached to the net, the streamer, c, in this case extending in a rearward direction, if desired to such an extent that the boards lie behind the net.

Any other convenient form of attachment may be used.

Or again, a series of such boards with varying proportions of lift and spread may be attached to the head rope of the net so as to keep the latter open both laterally and vertically.

Apart from the attachment of the relative rope or ropes to the apex of the board, the latter is entirely free to assume its natural position when moving through the water.

It will be seen that a board according to the present invention has no re-entrant angle between the towing warp and the body of the board or in the body of the board itself and is thus less likely to foul obstructions.

Various modifications may be made in the contour or structure of the improved board without exceeding the scope of the invention.

Having now described my invention, what I claim as new and desire to secure by Letters Patent is:—

1. A trawl board of the kind indicated having a front board-like part of the shape of a triangle, said triangle having a base and a leading apex opposite said base, for the attachment of said towing warp; and a rear board-like part secured to said base of said front part and at an angle to the plane thereof.

2. A trawl board as claimed in claim 1, in which also said rear part has the shape of a plane triangle.

3. A trawl board of the kind indicated formed of two plane triangular parts secured to one another base to base, the apex opposite the base of one of said parts providing the sole point of attachment for the towing warp.

4. A trawl board as claimed in claim 3, in which said parts take the form of right-angled triangles and said bases are constituted by sides of said triangles other than the hypotenuses.

5. A trawl board as claimed in claim 3, in which said parts take the form of right-angled triangles with the right angles juxtaposed.

6. A trawl board of the kind indicated formed of two board-like parts angled together about a connection running in a certain direction, one of said parts converging from said connection to an apex providing the sole point of attachment for the towing means.

7. A trawl board of the kind indicated, comprising front and rear board-like parts angled to one another about a certain connection disposed obliquely to the line of advance of said board, to form an open trough, said board streaming freely from a leading point of said front part remote from said connection, said leading point providing the sole point of attachment for the towing means.

8. A trawl board of the kind indicated, comprising front and rear board-like parts angled to one another to form a dihedral angle directed downwards when said board is towed and open above, said board streaming freely from a leading point of said front part remote from the junction of said board-like parts, said leading point providing the sole point of attachment for the towing means.

9. A trawl board of the kind indicated, comprising a front board-like part converging to a leading apex and a rear board-like part angled to said front part to form an open trough, said board streaming freely from said leading apex which provides the sole point of attachment for the towing means.

10. A trawl board of the kind indicated, comprising a front board-like part having a straight-line base and sides converging to form a leading point providing the sole point of attachment for the towing means; and a rear board-like part secured to said straight-line base of said front part and inclined at an angle to said front part, said board-like parts forming an open trough.

In testimony whereof I have signed my name to this specification.

JOHN FRANCIS HARVEY TEMPLER.
